ABSTRACT OF THE DISCLOSURE

A cigarette in which a wad of filter material abuts the tobacco, but is spaced from the mouthpiece end of the wrapper to provide an air space between said end and the filter, the wrapper and filter being tapered from approximately midway of the filter throughout the air space 15 area to a mere slit at the end of the wrapper.

The object of the invention is to provide a filter-cigarette having a tapering mouthpiece end portion wherein the tapered portion extends from the middle portion of the length of the filter to the mouthpiece end thereof and having an air space between the mouthpiece end of the cigarette and the downstream end of the filter.

Other features and the advantages of the present invention will be apparent from the following description, reference being had to the accompanying drawing wherein in a preferred embodiment of the invention is illustrated.

In the drawing:

FIG. 1 is a perspective view of the improved cigarette;
FIG. 2 is a side view of the cigarette;
FIG. 3 is a longitudinal sectional view of the cigarette; and

FIGS. 4 and 5 are front and rear views looking, respectively, in the direction of arrows 4—4 and 5—5 of FIG. 2.

Referring more in detail to the drawing, which shows a cigarette 20 including an integral wrapper formed of standard cigarette paper. The tobacco 22 and the wad of filter material 24 are confined in the wrapper. While not limited thereto, the tobacco area is 2 3/4 inches and extends from the right end of the cigarette, as viewed in FIGS. 2 and 3. One end of the filter 24 abuts the left end of the tobacco. It has a length of approximately 13/16 inch; it terminating approximately 7/16 inch from the left end of the cigarette, thus providing an air space 26 at the left end of that length.

The left portion of the cigarette 20 is tapered from approximately midway of the longitudinal length of the filter and increases progressively in its major axis and 50 decreases continually progressively in its minor axis to the extreme left end where the mouthpiece will be almost flat, as more clearly shown in FIG. 1.

While I have shown the lip end of the cigarette somewhat wider in cross section, the wrapper can be designed 55 so that when tapered, the extreme left end will have approximately the same perimeter in section, as the right end.

It has been found, by actual test of several individuals over a period of time, that when any one of the standard brands of cigarettes is provided with a filter and air space and with a taper as herein shown, throat irritation and coughing were materially reduced. The theory is not understood.

2

While the form of embodiment herein shown and described, constitutes preferred form, it is to be understood that other forms may be adopted falling within the scope of the claims that follow.

I claim:

1. A cigarette comprising in combination:
  - (A) an elongated integral wrapper formed of standard cigarette paper;
  - (B) cigarette tobacco being encased in the wrapper from one end throughout a major portion of the wrapper;
  - (C) an elongated wad or filter material having one end abutting the inner end of the tobacco, the other end of the wad being spaced from the opposite end of the wrapper to provide an air space between the wad and said opposite end of the wrapper, the wrapper and the wad being tapered from an area intermediate the longitudinal length of the wad to said opposite end of the wrapper to form a mouthpiece which is narrow and elongated transversely of the elongated wrapper, the remainder of the wad and the wrapper having constant transverse dimensions.
2. A cigarette as defined in claim 1, characterized in that the wad is approximately 13/16 inch in length.
3. A cigarette as defined in claim 1, characterized in that the air space is approximately 7/16 inch in length.
4. A cigarette as defined in claim 1, characterized in that the wad is approximately 13/16 inch in length and the air space is approximately 7/16 inch in length.
5. A cigarette as defined in claim 1, characterized in that the wad is approximately 13/16 inch in length and that the length of the tobacco area is approximately 2 3/4 inches.
6. A cigarette as defined in claim 1, characterized in that the air space is approximately 7/16 inch in length and that the length of the tobacco area is approximately 2 3/4 inches.
7. A cigarette as defined in claim 5, characterized in that the air space is approximately 7/16 inch in length and that the length of the tobacco area is approximately 2 3/4 inches.
8. A cigarette as defined in claim 1, characterized in that the tapered portion is elliptical in cross section with the major axis increasing progressively and the minor axis decreasing progressively to the said opposite end of the wrapper.
